UNITED STATES PATENT OFFICE

ALBERT MASTER, OF PARK RIDGE, ILLINOIS

HOIST

Application filed October 24, 1927. Serial No. 228,112.

The invention relates generally to hoists and more particularly to power driven hoists capable of receiving the driving power from a source such as a motor vehicle.

5 The primary object of the invention is to provide a new and improved hoist which is adapted to be readily attached to or removed from a suitable source of power.

It has generally been customary in the art 10 pertaining to devices of this character to provide hoists in which a reversing action of the power drive is essential to effect a raising and lowering movement thereof. This feature has been objectionable since the manipulation of such a hoist is a complicated operation. Another object of the invention therefore is to provide a detachable hoist in which 15 operation thereof is effected by a driving means which moves constantly in one direction.

Another object of the invention is to provide a hoist which may be readily attached to a motor vehicle to be driven thereby, which hoist includes a manual control enabling an 20 operator, at will, to effect a raising or lowering action of the hoist, to stop and hold the hoist at any desired point or instant, and to permit the hoist to remain idle independently of the movement of the driving means.

30 Other objects and advantages will become apparent from the following detailed description of the preferred embodiment of the invention and in the accompanying drawings, in which:

Figure 1 is a front elevation of the invention secured to the wheel of a motor vehicle, part of the operating handle being broken away.

40 Fig. 2 is a central section thereof taken on the line 2—2 of Fig. 1 looking in the direction of the arrows.

Fig. 3 is an enlarged fragmentary section 45 showing the braking mechanism and is taken on the line 3—3 of Fig. 2 looking in the direction of the arrows.

Fig. 4 is an enlarged front view of a part 50 of the clutch mechanism.

Fig. 5 is an enlarged detail view of a part 55 of the braking mechanism.

Fig. 6 is a fragmentary view in perspective on a reduced scale showing the invention as mounted on a motor vehicle.

While a particular advantage of the hoist 60 illustrated herein resides in the adaptability of the hoist to be incorporated on any form of motor vehicle, and while it is illustrated and will be described in this capacity, it will be understood that the hoist is quite as readily capable of being permanently attached 65 to a stationary driving means, such as an electric motor or gasoline engine or the like.

Describing the invention first in a brief 70 general manner, the hoist comprises a securing base 10 preferably mounted permanently on one of the wheels 11 of a vehicle which is, in this instance, the left rear wheel. The hoist proper is secured to the base 10 in any manner permitting rapid attachment and detachment therefrom and includes a stub 75 shaft or auxiliary axle, generally designated 12, arranged to rotate with the wheel. A winding drum 13 is rotatably mounted on the shaft 12 and has on one side thereof a driving connection with the shaft through the intermediate agency of a clutch mechanism 14. The drum is also arranged to be engaged by means of a suitable friction brake device 15 for preventing the rotation of the drum.

An operating lever or handle 16 is provided for the manipulation of the hoist and is so arranged with respect to the clutch and brake mechanisms that neither will interfere with the operation of the other. That is to say, the clutch and the brake operate individually and such operation is controlled by the single manually operable handle or lever 16 which upon movement in one direction effects a driving engagement between the shaft and the drum and upon movement in 80 the opposite direction actuates the brake.

Referring to Fig. 2, the securing base 10 is herein shown as a suitably formed ring of sufficient size to fit about the hub 17 on the outer surface of the wheel 11. The ring is adapted to be secured permanently upon the wheel to which end a plurality of U-shaped bolts 18 are appropriately disposed about the outer periphery of the ring to be fitted 95 around certain of the spokes 19 of the wheel. 100

During the operation of mounting the ring on the wheel, the ring is preferably "trued" or mounted squarely thereon with the axis of the ring and wheel coinciding so that the ring may revolve in a vertical plane about the same axial center as the wheel.

The shaft 12, which is preferably hollow, comprises what may be termed the axle of the hoist and is arranged to be secured to and rotate at all times with the ring 10. The shaft, in this embodiment, is constructed to provide three separate external bearing surfaces, of which the inner and the largest diameter surface 20 provides a surface upon which the brake device 15 is mounted, the outer and smallest diametered surface 21 provides a mounting for the clutch device 14, and the intermediate surface 22, the diameter of which is intermediate the diameters of the brake and clutch surfaces, provides a bearing upon which the drum assembly 13 is mounted.

The shaft 12 adjacent the inner end has an integrally formed radial flange 23 thereon arranged to abut the ring 10 on the wheel 11. The flange 23 is spaced a short distance from the end of the shaft to provide an axially extending shoulder 24 which is accurately machined or otherwise finished to fit snugly within the correspondingly finished inner periphery of the ring.

The shaft may be securely mounted on the ring through the flange 23 in any preferred manner, as by providing a plurality of outwardly projecting studs 25 on the ring 10, which studs extend through appropriately positioned apertures 26 in the flange 23. The studs are screw threaded at their outer ends to receive a nut 27 thus securing the shaft 12 to the ring 10. By this construction the shaft may be properly positioned on the ring by the abutment of the shoulder 24 and the flange 23 with the ring and then be rigidly secured in place with a minimum expenditure of time and labor. Since the ring has been previously "trued" with respect to the wheel, the shaft will also be accurately mounted on the wheel. As may be seen in the drawings ample space is provided within the brake section of the drum to receive therein the hub-cap assembly of any vehicle.

The drum assembly 13 in this instance comprises a central portion or hub 28 having a pair of spaced outstanding circular walls 29, 30 thereon. The drum is somewhat shorter than the hub 28, which is substantially as long as the intermediate section 22 of the shaft, thus providing an extension which, in effect, is an axial sleeve 31 integral with the drum. The sleeve is arranged to be engaged by a part of the clutch mechanism as will be presently described. The outer wall 30 of the drum preferably carries thereon a means by which one end of a cable 32 may be secured to the hoist. This means as shown

in Fig. 1 comprises a bolt 33 permanently mounted on the wall 30 to extend outwardly therefrom and is screw threaded to receive a nut 34, between which and the wall of the drum the cable 32 may be secured. Since the cable is thus secured externally of the hub of the drum a suitable aperture 35 is provided in the wall through which the cable may be passed to be wound on the drum. In this construction the aperture is positioned relative to the securing means in such manner that the cable 32 will be drawn onto and released from the lower side of the drum.

The clutch mechanism 14 may be of any preferred construction which will provide a positive driving engagement between the shaft 12 and the drum 13. In this instance I have shown a clutch mechanism comprising an engaging member in the form of a split collar 36 (Fig. 4) which is mounted relatively loosely on the sleeve 31 of the drum 13. The collar 36 is adapted, when the winding drum is at rest, to rotate loosely upon the sleeve 31 and is formed of a suitable somewhat resilient material which permits the split ends 37, 38 of the collar to be drawn together thereby tightening the collar to such an extent that a frictional engagement between the sleeve 31 and the collar 36 is produced. At a suitable position upon the collar, which, in this instance, is diametrically opposed to the gap therein an integral radial lug 39 is provided which projects laterally beyond the sides of the collar. The laterally projecting portion is notched, as at 40, to receive and engage a member to be presently described.

A plate 41 of substantial thickness and preferably circular in shape is mounted about the smallest diametered or clutch section 21 of the shaft adjacent the outer end of the intermediate section 22 carrying the drum. The plate is secured to the shaft 12 for rotation therewith by any suitable means, such as the key 42. On one side of the plate 41 a radially extending finger 43 is formed which is adapted to extend into and be engaged by the notch 40 in the laterally projecting portion of the collar. In this manner, a driving connection with the shaft is provided for the collar.

The preferred form of the means by which the split ends 37, 38 of the collar 36 are drawn together to engage the collar with the drum sleeve 31 is shown in Figs. 2 and 4. On one split end of the collar, in this instance the end 37, a pair of axially spaced lugs 44 are provided which have registering openings therein to act as bearings for a pin 45. The pin is formed so that the portions thereof which are journaled in the lugs 44 are on the same axial center but that portion of the pin positioned between the lugs is constructed to provide a surface which is eccentric to the main axis of the pin. Means, such as the

eye-bolt 46, is mounted on the pin with the eye 47 thereof bearing on the eccentric surface, and the free end of the bolt extending loosely through an aperture 48 formed in a lug 49 which projects from the other split end 38 of the collar. A nut 50 screw threaded on the bolt 46 secures the parts in assembled relation and provides, in addition, a means for adjusting the fit of the collar 36 about the sleeve 31. The outer end of the pin 45 carries a finger 51 rigid therewith which extends diagonally from the pin to a position adjacent the clutch section 21 of the shaft and is normally held in such position by means of the spring 52 bearing between the plate 41 and the outer end 53 of the finger.

The clutch actuating means, generally indicated at 54 (Fig. 2) comprises a somewhat elongated tubular member mounted upon the outer end of the shaft 12 for rotational and sliding movement relative thereto. A beveled surface 55, which slants inwardly toward the shaft, is provided thereon and is arranged, upon sliding movement of the member inwardly of the shaft, to engage the end of the finger 51. In consequence of this engagement the finger is caused to swing away from the shaft 12, thereby rotating the pin 45, and the eccentric portion thereof which causes the bolt 46 to draw the split ends 37, 38 toward each other, and effect the engagement of the clutch collar 36 with the sleeve 31. The tubular actuating member 54 is retained on the shaft 12 in any suitable manner, preferably by such means as a circular plate 56 secured on the end of the shaft by the screws 57.

With respect to the braking mechanism 15, the preferred form of which is illustrated in Figs. 2 and 3, the assembly comprises a circular supporting member 58 which is mounted upon the largest diameter 20 or brake section of the shaft 12 with the shaft being permitted to rotate freely therein. The outer surface of the brake supporting member 58 carries a radially projecting annular flange 59 which has, at the outer circumference thereof, a second flange 60 overlying the surface of the support and substantially concentric therewith. At one side of the support the flange 59 is recessed and at this point a lug 61 projects radially from the support to which lug one end of a brake band 62 of any suitable material is secured. The brake band is constructed normally to lie within and contact the inner surface of the flange 60 and has secured to the inner surface thereof a brake lining 63 of suitable material. The flange 60 preferably is finished internally and provides a stop or limiting means which the brake band and lining normally abut when in inoperable position. Moreover, the diameter of the flange is such that, when in such position the desired amount of clearance between

the brake band and the friction member engaged thereby is obtained.

The brake band and lining encircles the major portion of the circumference of the support and in practice the distance between the ends of the brake band is approximately the distance between two supposititious lines which are diametrically tangential to the circle designated by the support 58. A second lug 64 outstanding from the support 58 at a point adjacent the free end of the brake band 62 has an aperture therethrough loosely to receive the shank of a bolt 65 which is secured to the free end of the brake band.

The engagement with the winding drum 13 by which the brake device stops and holds the drum from rotation is effected by such means as an annular flange 66 of substantial width which extends from the side 29 of the drum adjacent the brake mechanism, and is of a diameter to overlie the outer surface of the brake support 58 beneath the lining 63 of the brake band 62. The flange 66 may be formed and secured to the drum in any suitable manner, such as the integral construction shown herein.

The actuating means for the brake mechanism, with particular reference to Fig. 3, comprises preferably a means by which only a relatively small movement is necessary to effect the frictional engagement between the brake lining 63 and the flange 66 on the drum. To this end a relatively narrow, elongated link 67 is pivotally mounted on a rod 68 which in turn is journaled in a pair of ears 100 69 extending outwardly from the brake support 58 at points adjacent the lugs 61, 64. At one end of the link 67 (Fig. 5) are a pair of integrally formed fingers 70, which project substantially perpendicularly to the link 105 and which are adapted to extend on either side or "straddle" the shank of the bolt 65 which is connected to the free or movable end of the brake-band 62. In effect, the fingers, with the link, form a bell crank lever which acts to pull the bolt 65 through the lug 64 and tighten the brake band.

The fingers 70 in the normal position of the link 67 rest against the lug 64 through which the bolt 65 passes and are adapted to engage the bolt in a well known manner as by bearing upon a washer 71 held in place on the bolt by means of a nut 72 and lock nut 73 screw threaded thereon. Preferably a resilient means, such as the spring 74 bearing 120 between the lug 64 and the free end of the brake band, exerts a pressure which tends to maintain the parts in their normal positions.

A second pivot rod 75 bearing, as at 76, 125 in the opposite side of the link 67, provides a pivotal mounting for a connecting member 77 herein having the form of a V-shaped arm which is pivotally mounted near each end of the rod 75.

Since the supporting member 58 is freely and rotatably mounted upon the shaft 12, means is provided to prevent rotary movement thereof when force is applied to stop the drum. To this end a substantially triangular boss 78 extends radially from the support at a position substantially diametrically opposed to the link 67. The outer apex of the boss terminates in a tubular socket 79 adapted to receive one end of a bar 80. The bar may be secured in the socket in any preferred manner, as by the bolt 81, extending through both members, and is of such length, determined by the desired operating position of the hoist, as to rest upon the ground when the hoist is in that desired position. Thus when the brake moves into or is in engagement with the drum, the force or pull on the drum and brake support is restrained by the bar.

It will be seen that by this construction a swinging movement of the link 67, which, in this embodiment, is in an inward direction toward the wheel 11, will cause the brake lining 63 to be drawn into frictional engagement with the flange 66 through the intermediate agency of the fingers 70.

The construction which has thus far been described includes a drum adapted to receive thereon the coil of rope, wire, cable or the like, which drum is under the controlling agencies of a clutch mechanism for driving the drum in the winding direction and a brake mechanism for holding the drum stationary and for controlling it while the cable is being paid out. In order that the manual manipulation of the hoist may be as simple as possible, it will be observed that in the present embodiment the movements or forces which actuate the clutch and brake mechanisms are directed substantially axially of the hoist in opposite directions. Thus a single hoist operating means such as the handle or lever 16 may be employed to provide a selective engagement of the clutch and brake mechanisms. The handle is a substantially rigid member which is of a length to extend forwardly of the vehicle chassis (diagrammatically shown as 82 in Fig. 6) to a convenient position adjacent the driver's seat. The lower end of the lever is divided to form a yoke 83 (Fig. 1) having apertures therein adapted to engage a pair of diametrically opposed studs 84 carried by an annular ring member 85 (Fig. 2) which loosely fits in an annular groove 86 on the surface of the tubular clutch actuating member 54. For convenience in assembly, the ring member 85 may be split and the abutting ends detachably secured together, as by means of bolts 85^a. Suitable means, such as the bolt 87, may be provided to prevent spreading of the arms of the yoke 83. In the apex of the V-shaped connecting arm 77 an aperture is provided which receives the free end of a connecting

member in the form of a rod 88 pivotally mounted, as at 89, on the lever 16. The rod is adjustably and detachably secured to the arm 77, in this instance, by the nuts 90 screw threaded on the free end thereof. A supporting member 91 (Fig. 6) may be hinged or otherwise swingably secured to the lever 16 at an appropriate point for the purpose of supporting the free end of the lever in its proper position relative to the vehicle seat. The lower end of the rod 91 rests on the ground.

Engagement of the clutch mechanism to drive the drum is obtained by moving the lever 16 outwardly from the vehicle body (which is to the left in Fig. 6). The lever pivots with the point of attachment of the connecting arm 77 as a fulcrum and the yoke end of the lever is swung inwardly of the hoist shaft to slide the tubular member 54 inwardly thereof to engage the clutch.

A movement of the lever in a reverse direction (to the right in Fig. 6) first causes the return of the clutch to its inoperative position. Further outward movement of the yoke end of the lever being limited by the contact of the tubular member with the circular plate 56 on the end of the shaft, the lever pushes, as it were, against the V-shaped connecting arm 77, to swing the link 67 to the right to actuate the brake mechanism 15. The intermediate point between the two extremes of movement of the lever is a neutral position in which the shaft 12 may rotate idly without operating any part of the hoist mechanism. It will be observed that, when the brake mechanism is in engagement to hold the hoist, the drum tends to rotate clockwise or in the direction of the arrow (Fig. 3). Such a tendency operates, in the engagement of the drum and brake band, to force the brake into a closer, more firm frictional engagement with the drum since the direction of the force is away from the fixed end of the brake-band.

Under certain circumstances it is contemplated that the cable might be released or unwound from the hoist with greater rapidity than is necessary, which might cause the cable to become loosened and permit it to move from the drum with a resultant tangling or snarling thereof. In order to prevent this occurrence, means is provided which is stationary relative to the drum and which extends across the gap or space between the side walls of the drum to prevent the cable from accidentally moving off the drum over the side walls thereof when the cable becomes loosened. In this instance such a means comprises a plurality of tubular members 92 which are screw threaded or otherwise suitably secured in a like number of bosses 93 formed about the periphery of the brake supporting member 58. The tubular members extend outwardly from the support substantially parallel to the axis of the hoist and are

positioned closely adjacent the peripheral edges of the side walls of the drum. Thus, if the cable by any chance becomes loosened upon the drum the tubular members act as stops which confine the coils upon the drum.

5 In operation the hoist is attached to the securing base, which is permanently mounted on the driving wheel of the vehicle, after that wheel has been raised or "jacked up" from the ground. The remaining wheels must, of course, be suitably blocked or otherwise secured to prevent movement of the vehicle during the operation of the hoist. After the hoist has been attached on the vehicle, 10 the cable, which is generally carried upon the drum when the hoist is not in use, is led through the usual pulleys and the like (not shown) which are necessary in the particular hoisting job to be done.

15 Due to the construction of the hoist, the operating handle or lever will extend to convenient position adjacent the driver's seat where the operation of the hoist may be controlled in the manner which has been previously set forth. It will be apparent that 20 the hoist may be conveniently operated since the operator is in a position at all times to observe the raising and lowering action of the hoist. Thus, when it is desired to raise 25 some object, the operator may move the lever outwardly to engage the clutch and initiate the hoisting movement. The speed at which 30 the hoist operates may be controlled by the speed of the motor operating through any of the customary change speed gears in the 35 transmission. When the object being hoisted has been lifted to desired height, the lever may be moved rapidly inwardly to disengage the clutch and to engage the braking 40 mechanism regardless of the speed at which the hoist has been operating. The lowering movement of the hoist is controlled solely by the braking mechanism which may be entirely disengaged to permit a rapid lowering of 45 an object or which may be slightly engaged to effect a slower controlled descent of an object. Obviously the hoist is capable of being controlled either from the seat of the vehicle, as has been described, or by an operator 50 standing on the ground. If an object is to be hoisted to a considerable height, it is preferable to operate the hoist from a position on the ground where better vision is possible. In such event, suitable means, as wires or the 55 like, would be used in controlling the speed of the motor from the remote position but the operation of the hoist would remain precisely the same.

60 While the invention is susceptible of various modifications and alternative constructions, I have shown in the drawings and have herein described in detail the preferred embodiment, but it is to be understood that I do not thereby intend to limit the invention to the specific form disclosed, but intend to

cover all modifications and alternative constructions falling within the spirit and scope of the invention as expressed in the appended claims.

I claim as my invention:

1. A detachable hoist for motor vehicles comprising, in combination, a base adapted to be permanently mounted upon a driving wheel, a shaft, means for detachably securing said shaft to said base so that the axis of 70 said shaft and the axis of said wheel coincide, a drum rotatably mounted upon said shaft, a clutch mechanism mounted on said shaft and arranged to engage said drum to effect a driving connection between said drum and 75 said shaft, and a brake mechanism mounted on said shaft and adapted to engage said drum to hold said drum against rotation with the shaft.

2. A detachable hoist for motor vehicles 80 comprising, in combination, a base adapted to be permanently mounted upon a driving wheel, a shaft, means for detachably securing said shaft to said base so that the axis of 85 said shaft and the axis of said wheel coincide, a drum rotatably mounted upon said shaft, a clutch mechanism mounted on said shaft and arranged to engage said drum to effect a driving connection between said drum and 90 said shaft, a brake mechanism mounted on said shaft and adapted to engage said drum to hold said drum against rotation with the shaft, and a single operating 95 means connected to said clutch and said brake mechanisms adapted to effect an engagement of one or the other of said mechanisms at the option of the operator.

3. A detachable hoist for motor vehicles comprising, in combination, a shaft, means for detachably securing said shaft to one of 105 the driving wheels of the vehicle, a drum mounted on said shaft for rotational movement relative thereto, and a clutch mechanism mounted on said shaft and adapted frictionally to engage said drum to provide 110 a driving connection between said shaft and said drum.

4. A detachable hoist for motor vehicles comprising, in combination, a base permanently mounted on a driving wheel, a shaft 115 adapted to be detachably secured to said base, a cable receiving member rotatably mounted on said shaft, means providing a releasable driving connection between said member and said shaft, and means adapted to engage said 120 member to effect relative movement between said shaft and said member.

5. A hoist having, in combination, a driving means, a shaft adapted to be driven thereby, a drum mounted on said shaft for rotation 125 relative thereto, a clutch mechanism mounted on one end of said shaft providing an intermediate connection between said shaft and drum, a brake mechanism mounted on the other end of said shaft and adapted to en- 130

gage said drum to hold said drum against a driving movement by said shaft, and operating means connected to said clutch and brake mechanisms and arranged selectively to control the operation of said clutch or brake mechanisms.

6. A hoist having, in combination, a driving means, a driven shaft, means for securing said driven shaft to said driving means, 10 a cable receiving drum mounted substantially intermediate the ends of said driven shaft for relative rotation therein, a clutch mechanism mounted on one end of said shaft and providing an optional driving connection between said drum and said shaft, a brake mechanism mounted on the other end of said shaft and adapted to engage said drum to effect movement thereof relative to said shaft, and an operating means connected to said clutch 15 and brake mechanisms and movable axially of said shaft selectively to effect the engagement of either of said mechanisms.

7. A hoist having, in combination, a driving means, a driven shaft secured thereto, a cable receiving drum mounted on said shaft for rotation relative thereto, a clutch mechanism having a part movable axially of said shaft to effect a driving engagement between said drum and said shaft, a brake mechanism including a member movable axially of said shaft to effect the engagement of said brake mechanism with said drum, and an operating means connected to the axially movable part of said clutch mechanism and to the axially movable member of the brake mechanism whereby movement of said operating means axially in one direction will move said clutch into engagement to drive said drum, and movement of said operating means in the other direction will effect the engagement of said brake mechanism with said drum.

8. In combination with the chassis of a motor vehicle, a shaft adapted to be mounted on one of the driving wheels of said vehicle, 45 means for detachably securing said shaft to said wheel, a cable receiving drum mounted on said shaft, a clutch mechanism positioned intermediate said shaft and drum to provide an optional driving connection therebetween, a brake mechanism adapted to engage said drum to hold said drum against movement by said shaft, and a single operating lever connected to said clutch and brake mechanisms for effecting the engagement of either with 50 said drum, said lever being arranged to extend forwardly of the chassis of said vehicle to a position adjacent the operator's seat, whereby the operation of said hoist may be effected from a position near the front end 55 of the vehicle.

9. In combination with the chassis of a motor vehicle, a shaft adapted to be secured to one of the driving wheels of said vehicle, a cable receiving drum carried by said shaft, 60 a clutch mechanism and a brake mechanism

carried by said shaft and adapted to engage said drum to control the movement of said drum relative to said shaft, and an operating lever connected to both of said mechanisms and extending forwardly of said chassis to a position adjacent the driver's seat.

10. A detachable hoist for motor vehicles having, in combination with a driving means on said vehicle, a shaft secured to said drive means, a drum mounted on said shaft, means 75 providing an optional driving connection between said drum and said shaft, a brake mounted on said shaft for rotational movement relative thereto and adapted to engage said drum to hold said drum against driven movement by said shaft, said brake mechanism including a means adapted to engage the surface on which said vehicle rests to hold said brake against movement with said drum when said brake and drum are engaged.

11. A hoist adapted to be actuated by a motor vehicle comprising, in combination, a shaft, means for securing said shaft to one of the driving wheels of the vehicle, a drum rotatably mounted on said shaft, a brake mechanism carried upon said shaft and adapted to engage said drum to prevent rotation of said drum with the shaft, said brake mechanism including a radially extending member adapted to engage the ground to hold 95 said brake mechanism in a fixed position relative to the movable parts of said hoist.

12. A detachable hoist for motor vehicles comprising, in combination, a base, means for mounting said base permanently upon a 100 driving wheel of said vehicle, a shaft, means for detachably securing said shaft to said base, a drum rotatably mounted upon said shaft, means providing a releasable driving engagement between said drum and said 105 shaft, a brake mechanism rotatably mounted upon said shaft adapted to engage said drum to prevent rotation of said drum with the shaft, said brake mechanism including a member adapted to engage a stationary object to prevent rotation of said brake mechanism about said shaft.

13. A detachable hoist for motor vehicles comprising, in combination, a shaft, means for detachably securing said shaft to one of 115 the driving wheels of the vehicle, a cable receiving member rotatably mounted on said shaft, and means operable to control the relative movement of said cable receiving member with respect to said shaft.

14. A device of the character described comprising, in combination with a driving means, a shaft adapted to be mounted on said driving means, interengaging means on said shaft and said driving means for definitely 120 locating the axis of said shaft in alignment with the axis of said driving means, means for detachably securing said shaft to said driving means, a cable receiving drum mounted on said shaft for rotation relative 130

thereto, and a clutch mechanism positioned intermediate said drum and said shaft for providing an optional driving connection therebetween.

5 15. In a device of the character described, the combination of a prime mover, and a hoist mechanism arranged to be detachably secured thereto, said hoist mechanism comprising a shaft, means providing a detachable connection between said shaft and said prime mover, a cable receiving drum mounted on said shaft for rotation relative thereto, clutch means for drivingly connecting said shaft and said drum, and brake means 10 adapted to engage said drum against movement with said shaft.

15 16. A device of the character described comprising, in combination, a prime mover, a base permanently attached to said prime mover for rotation therewith, a shaft adapted to be mounted on said base with the axis of said shaft in alignment with the axis of said prime mover, means for detachably securing said shaft to said base, a drum rotatably 20 mounted on said shaft, and means controlling the movements of said drum relative to said shaft.

25 17. A device of the character described comprising, in combination with a driving means having a base permanently mounted thereon, a shaft adapted to be mounted on said base, interengaging means on said shaft and base for definitely positioning said shaft on said base so that the axis of said shaft will 30 be in alignment with the axis of said driving means, means for detachably securing said shaft to said base, a drum rotatably mounted on said shaft, and means controlling the movements of said drum relative to said 35 shaft.

40 18. In a device of the character described, the combination of a driving means having an annular ring mounted thereon concentrically with respect to the axis thereof, and a 45 hoist mechanism adapted to be detachably secured to said ring including a shaft having an annular flange thereon concentric with respect to the axis of said shaft, said flange being of such size as to snugly abut 50 said ring when said shaft is mounted thereon whereby the axis of said shaft is definitely located in alignment with the axis of said driving means, and means for detachably securing said shaft to said ring.

55 In testimony whereof, I have hereunto affixed my signature.

ALBERT MASTER.
